UNITED STATES PATENT OFFICE.

JOHN B. AUFULDISH, OF DAYTON, OHIO.

DESIGN FOR A STOOL-LEG.

SPECIFICATION forming part of Design No. 27,598, dated August 31, 1897.

Application filed July 19, 1897. Serial No. 645,174. Term of patent 3½ years.

To all whom it may concern:

Be it known that I, JOHN B. AUFULDISH, a citizen of the United States, residing at Dayton, in the county of Montgomery and State of Ohio, have invented and produced a new and original Design for a Stool-Leg, of which the following is a specification, reference being had to the accompanying drawing, forming a part thereof.

As shown in said drawing, the leading or material feature of my design consists in a leg for a stool with two oppositely-projected curves in the intermediate or body portion thereof, with the upper terminal of said leg terminating in a horizontal plane and the lower end thereof terminating in a vertical plane.

The upper portion of the leg lies in a horizontal plane and terminates in a flat plate-like form A. From this point it assumes a circular form in cross-section and extends down-

wardly in a half-circular curve B, thence inwardly in a half-circular curve C and outwardly, with its lower end D terminating in a vertical plane and fitted with a spherical piece or ball E, which is surmounted with a ring F. When the leg is given such curvilinear form, the vertical plane of the curve B lies approximately in a plane with the lower end D, and the vertical plane of the curve C lies approximately in a plane with the longitudinal center of the upper horizontal terminal A.

I claim—

The design for a stool-leg herein shown and described.

In testimony whereof I affix my signature in presence of two witnesses.

JOHN B. AUFULDISH.
